DRAFT GEAR

Harry W. Mulcahy, Chicago, Ill., assignor to W. H. Miner, Inc., Chicago, Ill., a corporation of Delaware

Application August 9, 1954, Serial No. 448,411

4 Claims. (Cl. 213—45)

This invention relates to draft gear for railway draft rigging.

It is a main object of the invention to provide in a draft gear for railway draft rigging a compensating device for maintaining the gear tight in the yoke and pocket of a vehicle.

Another object of the invention is to provide in a draft gear as set out in the previous paragraph, key means registerable with the casing members to maintain the gear as a unitary structure for shipping and to facilitate installing the gear in the yoke of a railway draft rigging.

Another object of the invention is to provide in a compensating device for railway draft rigging, a resilient column maintained under compression to maintain the gear tight in the yoke and to provide for limiting the maximum compression to which the compensating column may be subjected.

Further objects of the invention not specifically mentioned here will be apparent from the detailed description and claims which follow, reference being had to the accompanying drawings in which a preferred embodiment of the invention is shown by way of example and in which:

Figure 1 is a plan view of the draft gear installed in the rigging;

Figure 2 is a cross sectional view through the horizontal median plane of the gear, with the keys in place for shipping;

Figure 3 is a fragmentary view, partly in section, showing the gear installed in a yoke and pocket of normal length;

Figure 4 is a fragmentary view, partly in section, showing the gear installed in a yoke that is shorter than the pocket;

Figure 5 is a fragmentary view, partly in section, showing the gear installed in a yoke that is longer than the pocket;

Figure 6 is a rear elevational view of the gear with the keys in place for shipping;

Figure 7 is a rear end elevational view of the compensator housing; and

Figure 8 is a rear end elevational view of the compensating plunger.

Draft gears for railway draft rigging fit within the yoke of the rigging and into a pocket between the sills and floor of the vehicle, which pocket is defined in length by lugs secured to the sills. The usual draft gear consists of a casing enclosing a resilient column that is maintained under compression and bears against a pressure applying means to keep that means projecting from one end of the casing. The rear end of the casing bears against the rear lugs and rear end of the yoke. A follower bears against the pressure applying means and front lugs. Such an arrangement keeps the gear tight in the pocket and yoke only when the length of the pocket and yoke are the same, and when the pocket and yoke are of unequal lengths unwanted slack will result.

It is to the keeping of the gear tight in the pocket and

2

yoke, notwithstanding variations in the lengths thereof, that the present invention is particularly directed.

In its preferred form the gear of the present invention consists of two casing members, each open at one end and these members are aligned with the open ends adjacent. Within the casing is a resilient column and a compensator housing. Within this housing is a resilient compensating column and a plunger which projects therefrom and through an opening in the rear end of the rear casing member. When in the pocket the front casing member bears against the front lugs and the yoke and the rear casing member bears against the rear lugs. The plunger bears against the rear end of the yoke. Both the main resilient column and the resilient compensating column are maintained under compression normally and the gear is maintained tight in the pocket and yoke, notwithstanding variations in the lengths thereof.

As will be seen in the drawings, particularly Figures 1 and 2, the gear of the present invention consists of a front casing member A, a rear casing member B, a main resilient column composed of a plurality of resilient pads C arranged in groups with separators D interposed between the groups, one of the separators E bridging the gap between the adjacent ends of the casing members A and B. Fitted within the rear casing member B is a compensating housing F in which a compensating plunger G is fitted and urged outwardly of the housing by a compensating resilient column H that is maintained under compression at all times.

Casing members A and B are provided with perforations with which keys K may be registered when the casing is shortened slightly below its normal length, the keys serving to hold the gear together as a unit to facilitate shipping and serving also to maintain the overall length of the gear and compensating plunger slightly less than the length of the opening in the yoke, thereby to facilitate installing the gear in the yoke.

The front casing member A in the embodiment shown by way of example is of rectangular cross section having a solid front wall 10 that engages the front lugs 11 of the pocket and also engages the yoke 12. Side walls 13 of the front member A contain perforations 14 into which the keys fit. The front wall 10 contains rearwardly extending projections 15 by which the resilient column units C are maintained in place with respect to the member A.

The rear casing member B is provided at its rear end with inwardly turned flanges 16 and 17, defining between them a rectangular opening 18 centered in the end of the member. It will be noted that the flanges 17 are thinner than the flanges 16, forming a groove 19 that opens outwardly of the rear end of the member. Side walls 20 of the member B are provided with perforations 21 into which the keys K are registered.

Within the rear casing member B is a compensating housing F comprising a front wall 22, from which flanges 23 and 24 project into engagement with the flanges 16 and 17, respectively. The front wall 22 contains bosses 25 and sockets 125 by which the resilient pads C and the compensating column H are maintained in place with respect to compensating housing F.

The compensating plunger G comprises a flanged base portion 26 that telescopes between the flanges 23 and 24 of the housing and engages flanges 16 and 17 of the casing member B. The compensating plunger is provided with a main section 27 that projects beyond the flanges 16 and 17 and is adapted to engage the yoke of a draft rigging.

Within the compensating housing F is a resilient compensating column H which, in the example shown, consists of rubber pads bonded to metal plates, which pads are of known design. The pads contain sockets into

which bosses 25 register and bosses 28 that project into sockets 29 in the base 26 of the plunger to maintain a resilient column in alignment.

In the example shown, the main resilient column consists of three groups of pads of known design, which are fitted between the front wall 22 of the compensating housing and the front wall 10 of the front casing member A. Separators D are provided with flanges 30 that engage the side walls of the casing members to maintain the column against lateral movement under the forces of compression.

As will be seen best in Figure 2, separator E is of I-section, having a web 35 from both faces of which flanges 36 project, these flanges being of such dimension as to span the gap between the adjacent ends of the side walls of casing members A and B.

In assembling the gear, casing member B is placed with flanges 16 and 17 lowermost, the compensating plunger G is then inserted, compensating column members H registered with the plunger, and the housing F then installed in place. The main resilient column is then added, with separators D and E interposed, after which the front casing member A is added. It will be noted that centering the first pad C with respect to the front wall 22 of housing F is facilitated by bosses 31 at the corners of the wall 22. With the casing member B in assembling position, these bosses 31 project upwardly and the column member C drops into place between them. The main column is then compressed sufficiently to permit keys K to be registered with the perforations 14 and 21, after which the forces compressing the column are removed and the gear is held together as a unit by the keys. The gear is shipped with the keys in place and upon installation in a draft rigging the gear is fitted within the opening in the yoke and the keys then removed to permit installing the yoke and gear in the pocket of a vehicle.

In a yoke and pocket of the same length, the casing members A and B will be forced tightly against the lugs 11 and 40, as shown in Figures 1 and 3, and the compensating plunger 27 will be forced into engagement with the rear member 41 of the yoke. It will be noted in Figure 3 that the rearmost face of the plunger 27 is substantially aligned with the flanges 16 of the housing member B.

In case the opening in the yoke is shorter than the distance between the lugs 11 and 40, the flanges 16 project beyond the rear face of the compensating plunger 27 into engagement with the lugs 40 in the manner best seen in Figure 4, the rear portion 41 of the yoke moving into the groove 19 and the compensating plunger 27 moving into the compensating housing further compressing the compensating column H. In case the opening in the yoke is longer than the distance between the lugs 11 and 40, compensating plunger 27 is forced outwardly to maintain tight engagement with the rear portion 41 of the yoke in the manner shown in Figure 5.

In operation in buff, the portion 12 of the yoke acting upon the front wall 10 of the casing member A moves that casing member away from the lugs 11, thereby to compress the main resilient column. This rearward movement of the yoke causes the rear portion 41 thereof to move a corresponding distance, causing the compensating plunger 27 to be moved rearwardly until the base portion 26 thereof engages the flanges 16 and 17.

In draft, the yoke moves forwardly, pushing the compensating plunger 27 inwardly of the casing and compressing compensating column units H, this movement continuing until the yoke 41 engages flanges 17 of the casing member B. Additional forward movement of the yoke transmits forces directly to the casing member B, thereby to move it forwardly and compress the main resilient column rather than the compensating column.

Thus, it will be seen that the gear of the present invention

will be maintained tight in the pocket of a vehicle and in the yoke thereof, notwithstanding that there may be variations in the respective lengths of the pocket and yoke. The compensating column, which is of lower resistance than the main column, is compressed only to a limited extent and overloading of this column is thereby definitely prevented.

While I have chosen to illustrate my invention by showing and describing a preferred embodiment of it, I have done so by way of example only, as there are many modifications and adaptations which can be made by one skilled in the art within the teachings of the invention.

Having thus complied with the statutes and shown and described a preferred embodiment of my invention, what I consider new and desire to have protected by Letters Patent is pointed out in the appended claims.

What I claim is:

1. The combination with a railway draft rigging having a pocket defined by front and rear lugs fixed on the sills of a vehicle and having a yoke one end of which is disposed between the rear ones of said lugs; of a draft gear comprising a pair of casing members both of which are open at one end and one of which is closed at its other end, flanges projecting inwardly from the other end of the other one of said members defining an opening therein, said members being disposed with their open ends adjacent, a housing disposed in said other member and consisting of side walls engaging said flanges and extending therefrom to a main wall disposed parallel to the open end of the member; a main resilient column in said casing members one end of which abuts against said closed end and the other end abuts against said main wall, said main column being compressed by engagement of said closed end and said flanges with said lugs to maintain the gear tight in the pocket; a plunger comprising a main portion engaging said end of said yoke and extending through said opening to a base portion within said housing; a second resilient column within said housing and abutting against said main wall and said base, engagement of said plunger with said yoke compressing said second column to maintain the gear tight in the yoke.

2. The combination with a railway draft rigging having a pocket defined by front and rear lugs fixed on the sills of a vehicle and having a yoke one end of which is disposed between the rear ones of said lugs; of a draft gear comprising: a pair of casing members both open at one end; an end wall closing the front end of the front member; flanges projecting inwardly from the rear end of the rear member and forming an opening therein, said members being disposed with their open ends adjacent; a housing disposed in said rear member, said housing comprising a main wall disposed transversely of the member and side walls projecting rearwardly therefrom into engagement with said flanges; a main resilient column abutted at its front end against said end wall and abutted at its rear end against said main wall, said main column being compressed by engagement of said end wall with said front lugs and engagement of said flanges with said rear lugs to maintain the gear tight in the pocket; a plunger comprising a main portion engaging said end of said yoke and extending through said opening to a base portion disposed within said housing; a second resilient column in the housing abutting against said main wall and base, engagement of said plunger with said yoke compressing the second column to maintain the gear tight in the yoke.

3. The combination with a railway draft rigging having a pocket defined by front and rear lugs fixed on the sills of a vehicle and having a yoke one end of which is disposed between the rear ones of said lugs; of a draft gear comprising: a metallic casing member of rectangular cross section having an open end and a closed end, said closed end containing a rectangular perforation centered coincident with the end wall of the member, said end wall having thin sections above and below said perforation

forming a groove opening outwardly of the end wall, a second metallic casing member of rectangular cross section having an open end and a closed end, said members being disposed in alignment with their open ends adjacent; a compensating device within said first casing member comprising a housing, a plunger, and a resilient column engaging said housing and plunger; a main resilient column within said casing members and engaging said housing and the end wall of said second casing member, said end walls of said casing members engaging said lugs to maintain said main column under compression thereby to maintain said gear tight in the pocket; said plunger projecting through said perforation and engaging said end of the yoke thereby to maintain said compensating device column under compression to maintain the gear tight in the yoke, said yoke in draft moving said plunger inwardly of the gear further compressing said compensating column until the yoke engages the bottom of said groove after which further movement of the yoke moves said first casing member to further compress said main resilient column.

4. The combination with a railway draft rigging having a pocket defined by front and rear lugs fixed on the sills of a vehicle and having a yoke one end of which is disposed between the rear ones of said lugs and substantially in alignment therewith; of a draft gear comprising: a metallic casing member of rectangular cross section having an open end and a closed end, said closed end containing a rectangular perforation centered coincident with the end wall of the member, said end wall having thin sections above and below said perforation forming a groove opening outwardly of the end wall; a second

metallic casing member of rectangular cross section having an open end and a closed end, said members being disposed in alignment with their open ends adjacent; a device within said first member for compensating for 5 misalignment of said lugs and the end of the yoke comprising: a housing, a plunger and a resilient column engaging said housing and plunger; a main resilient column within said casing members engaging said housing and the end wall of said second casing member, said end walls of 10 said casing members engaging said lugs to maintain said main column under compression thereby to maintain said gear tight in the pocket; said plunger projecting through said perforation and engaging said end of the yoke thereby to maintain said compensating device column under compression to maintain the gear tight in the yoke despite misalignment of the yoke and lugs, said yoke in draft moving said plunger inwardly of the gear further compressing said compensating column until the yoke engages the bottom of said groove after which further movement of the yoke moves said first casing member to further compress said main resilient column.
